UNITED STATES PATENT OFFICE

ROBERT ADLER, OF ST. PAUL, MINNESOTA

INSERT FOR CONCRETE ROADS AND THE LIKE

Application filed June 17, 1929. Serial No. 371,451.

In the construction of hard surfaced roads from concrete and similar plastic compositions it has been found that when the material sets and contracts or settles, or is 5 heaved unequally, cracks are formed. Attempts have been made to control the location of such cracks and at the same time guard against unequal vertical movement of the adjacent parts of the road by embedding 10 metal strips in the forms of the plastic material so as to divide it into rectangular slabs. A device of the general type is described in United States Letters Patent Re-issue #16,202, granted November 10, 1925, 15 to Bernard Briody. The success of such device is dependent on the weakening effect of the strips, it being assumed that the adhesion of the concrete to the strips is less than the cohesion in the concrete. In practice, it has been found that such devices are 20 frequently ineffectual in controlling the location of the cracks because of the strong adherence of the plastic material to the strips in the finished structure.

25 It is the object of this invention to insure the formation of weakened lines in such plastic bodies by providing an insert composed of similar strips mounted face to face one against the other so that the concrete 30 covers and adheres to the outer surfaces only of the strips. More particularly, it is my object to provide an insert comprising a pair of contacting strips adapted to be embedded in a plastic body along a selected line, the 35 two strips being separable one from the other under contractive stress less than that required to separate the concrete from the faces of the strips.

The invention will be best understood by 40 reference to the accompanying drawings in which Figure 1 is a diagrammatic cross-section through a road, showing a suitable location for the insert; Fig. 2 is an enlarged plan view of my insert; Fig. 3 is an enlarged 45 fragmentary section taken on the line 3-3 of Fig. 1 and showing a suitable clip for excluding plastic composition from between the upper edges of the component members; Fig. 4 is a similar section showing separation 50 of the strips such as that caused by the

contracting of the concrete and also showing a suitable filler, such as tar or bituminous material in the crack and Fig. 5 is a vertical section through a slightly modified form of insert imbedded in plastic composition.

55 The insert comprises a pair of strips 6 and 7, preferably constructed from non-corrod़ing sheet metal and normally lying one upon the other face to face, with metal to metal contact. Extending longitudinally in 60 the strips 6 and 7 are corrugations 8 which interlock with each other, to form, when imbedded in the concrete or similar plastic body 9, a projecting flange 10 on one of the adjoining portions which engages a groove 65 in the other adjoining portion of the road to retain such portions in proper horizontal alignment. At their lower edges 11 the strips 6 and 7 are preferably joined together 70 or formed integral, as shown in the drawings, so that a hinge-like joint is formed which permits the upper edges of the strips to separate, as shown in Fig. 4, when the road material sets and contracts. To facilitate the operation of securing the inserts in 75 the concrete forms, a series of perforations or openings 17 (Fig. 2) are formed to extend vertically through the projecting corrugations 8. When the inserts are set up stakes 18 may be driven through the openings 17 80 into the sub-soil.

The strips 6 and 7 are placed in the concrete form along the lines where cracks are likely to develop, or where they are desired, and said strips are preferably so located that 85 their upper edges 12 are positioned a short distance beneath the upper surface 13 of the finished body. In some cases, I prefer to place a channel clip or member 14 over the upper edges 12 to exclude the concrete 90 therefrom, but this is unnecessary in most cases. Where the channel member 14 is used, it extends substantially to the surface 13 so that it can be removed when it is desired to fill the space formed by the contraction 95 of the material with tar, bitumen, or other filler 15 having the desired melting point.

In Fig. 5 is shown a pair of strips 6 and 7 which are formed with corrugations 16 of slightly modified form, and also showing 100

the strips without the use of the channel member 14 and formed with perforations 19 and 20 to interlock with the concrete. The perforations 19 and 20 are staggered so that 5 the plastic composition or concrete cannot extend through both strips 6 and 7 and thereby form a bond tending to prevent separation of said strips. Such perforations insure the adherence of the strips to the adjoining bodies of concrete when contraction 10 or other movements creating cracks take place. The perforations 19 and 20 may also be staggered as indicated in Fig. 2.

In use, the plastic composition 9 is poured 15 in the forms so as to completely imbed the strips 6 and 7 leaving an unbroken surface 13. When excessive strain develops either due to the contracting of the material or to 20 unequal settling or heaving, the cracks will develop along the lines weakened by the insert and the strips 6 and 7 will separate from each other, as indicated in Fig. 4, while adhering to the road material at their outer 25 faces. The filler 15 may be poured into the crack thus formed in well known manner, after removal of the clip 14, where such clip is used.

Having described my invention what I 30 claim as new and desire to protect by Letters Patent is:

1. An insert for dividing concrete or similar roads comprising, a pair of stiff, metal strips normally disposed in face to face contact with each other throughout their length 35 and connected together at their lower edges, said strips being adapted to be imbedded in the road body in substantially upright position and their upper edges being separable upon contraction of said body and registering, longitudinal corrugations in said strips 40 perforated to receive upright supporting means.

2. In a concrete or similar road, a pair of stiff, metal strips normally disposed in face to face contact with each other throughout 45 their length and connected together at their lower edges, said strips being imbedded in the concrete or like body in substantially upright position, their upper edges being separable upon contraction of said body, the 50 lower edges of said strips being substantially in the plane of the lower surface of the concrete and their upper edges spaced beneath the upper surface of the road and registering, longitudinal corrugations in said strips 55 perforated to receive upright supporting means.

In testimony whereof, I have hereunto signed my name to this specification.

ROBERT ADLER.
